BARTOW BEE COHEN, OF SHEFFIELD, ALABAMA, ASSIGNOR OF ONE-HALF
TO SHEFFIELD STOVE & FOUNDRY CO. AND ONE-HALF TO KING STOVE
& RANGE CO., BOTH OF SHEFFIELD, ALABAMA.

DESIGN FOR A STOVE.

No. 38,544.

Specification for Design.

Patented April 30, 1907.

Application filed March 26, 1907. Serial No. 364,738. Term of patent 14 years.

To all whom it may concern:

Be it known that I, BARTOW BEE COHEN, a citizen of the United States, residing at Sheffield, in the county of Colbert and State of Alabama, have invented a new, original, and ornamental Design for Stoves, of which the following is a specification, reference being had to the accompanying drawing, forming part thereof.

The figure is a perspective view of a stove showing my new design.

I claim:

The ornamental design for a stove as shown.

BARTOW BEE COHEN.
